UNITED STATES PATENT OFFICE.

WILLIAM CALVER, OF WASHINGTON, DISTRICT OF COLUMBIA.

MEANS FOR UTILIZING THE RAYS OF THE SUN.

SPECIFICATION forming part of Letters Patent No. 281,491, dated January 8, 1884.

Application filed April 18, 1883. (No model.)

To all whom it may concern:

Be it known that I, WILLIAM CALVER, a citizen of the United States, residing at Washington, District of Columbia, have invented 5 certain new and useful Improvements in Means for Utilizing the Rays of the Sun, of which the following is a specification, reference being had therein to the accompanying drawings.

This invention relates to certain improvements upon the patent granted me July 4, 1882, and has for its objects, in part, a greater accumulation of solar heat under certain circumstances, and this by an apparatus capable of use in or upon restricted areas; and the invention consists in certain features of construction and arrangement, which, with their further objects and advantages, will be hereinafter more particularly described, and the novelty thereof specifically set forth in the 20 claims.

Referring to the drawings, Figure 1 is a plan, Fig. 2 a side elevation, and Fig. 3 a modified arrangement, of an apparatus constructed and arranged in accordance with my 25 invention.

Like letters refer to like parts in all the figures.

As expressed in the title of this invention, the apparatus is capable of use in collecting, 30 accumulating, and storing for use any rays of the sun, be they chemical, heat, light, or any other rays, so that any of these may be employed for any useful purpose to which they are or may be hereafter found to be adapted. 35 In the present instance the heat-rays are mentioned and considered for the purpose of giving a clear understanding of the construction and use of the apparatus; and therefore it is deemed proper to state clearly that the ultimate 40 means of reception or application of the rays collected and any intermediate means of direction and collection or storage of the rays may be varied to suit the class of rays to be used—as, for example, opaque or other screens to separate the heat from the chemical or other rays may be employed, and other similar changes in the apparatus may be made without 45 a departure from my invention.

A, B, C, and D represent reflectors, which 50 may be of any desired construction, but which preferably are such as are shown in my above-mentioned patent. The reflectors A, B, and

C are mounted upon a car, E, adapted to revolve upon a track, F, which is a complete circle, three or more wheels, e, being provided 55 and secured in any desirable manner to the car. A second completely circular track, G, is arranged concentric with the track F, and upon said track G is mounted another car, H, carrying the reflector D. A bridge, I, in this 60 instance, extends directly from one car to the other, and upon the bridge a receiver, J, is located, so as to revolve with the cars and bridge in the direction indicated by the arrows, the top of Fig. 1 being considered north. 65 The receiver may be of any desired form or substance adapted to the purpose in view. It may be adapted to receive, retain, or direct and deliver the product of the reflectors, and, if used, any interposed screens, so that the 70 heat, light, or other rays of the sun may be put to practical use in or from the receiver. If for storing heat, the receiver J may be of the form and construction set forth in a companion application, Serial No. 91,478, here-with pending, or of such form and construction as shown in my said patent. The receiver or storage device J may be stationary 75 and in form a complete circle, and located between the two reflectors C and D, as shown by 8c dotted lines, Fig. 1. The bridge also supports secondary reflectors K K', each of which is mounted upon a vertical pivot. The number of reflectors upon either car may be increased or decreased, if desired; and, so far as 85 the entire apparatus is concerned, certain elements may be used separately or in conjunction with other devices than those shown.

The operation is as follows: The sun, being in the east, is reflected by the reflector D directly upon the receiver as the apparatus is turned upon the tracks, so that the center of the car E, the receiver J, and the reflector D, and the sun are in a line with each other, and the reflectors A, B, and C direct the rays upon 90 the opposite side of the receiver to that upon which the reflector D operates. In this manner the rays are constantly reflected, the cars being moved upon their tracks, and this, as well as the inclination of the reflectors, may 95 be accomplished by hand or automatically, as set forth in my said patent.

I have discovered in practice that by the use of secondary reflectors, as K K', the pri-

many reflectors A, B, C, and D may be presented more squarely to the sun, so that a much greater number of rays fall thereon and are utilized. By reference to Fig. 3 it will be seen that the reflector B may be turned directly toward the sun, when it will reflect the rays in a direction but little different from that from which they come and toward the secondary reflector K, by which said rays are directed upon the receiver J. The reflector B, being turned with the sun, acts directly upon the receiver at noon, and after meridian the secondary reflector K' is brought into action. By this arrangement of secondary reflectors the whole apparatus is rendered capable of use in restricted areas—as, for example, the roof of a building which is long and narrow—whereby a person can utilize the area at his disposal without trespassing upon adjacent roofs. Otherwise the secondary reflectors may be omitted. The bridge I is shown as broken, to indicate that the length thereof may be in accordance with any predetermined distance intervening between the two cars E H.

I do not broadly claim herein secondary reflection, or a reflector mounted on a car adapted to move upon a circular track, as these features are shown in my said patent.

It is apparent that the reflector D may be omitted, if desired, but not without loss of advantage, as in the position shown it subjects the receiver to the effect of the rays upon a side which otherwise would not be reached by the rays from the other reflectors.

By making the track or tracks completely circular, the apparatus is adapted to be presented toward the sun throughout the day to the best advantage, and this in spaces which, from uncontrollable circumstances, could not otherwise be fully utilized.

In my patent above mentioned I illustrated the use of a secondary concentrating-reflector to heat one side of the receiver; but in this case, and as illustrated clearly in the drawings, I am enabled to direct heat-rays upon both sides of the receiver, and this by a single reflection, and without concentration. This could not be accomplished by the apparatus shown in said patent.

Having described my invention and its operation, what I claim is—

1. The combination of a central pivoted revoluble reflector, and a receiver adapted to receive the rays from the reflector during its entire revolution, substantially as specified. 55
2. The combination of a central pivoted revoluble reflector, laterally-located secondary reflectors, and a receiver, substantially as specified.
3. The combination of a central pivoted 60 revoluble reflector, a concentrically-movable reflector, and an interposed receiver, substantially as specified.
4. The combination of a central reflector adapted to be revolved, with a receiver and 65 an outer reflector, both of which are adapted to be revolved concentrically and simultaneously with said central reflector, substantially as specified.
5. The combination of two circular concentric tracks, and cars adapted to move upon the same and carrying reflectors, with a connecting-bridge carrying a receiver, substantially as specified. 70
6. The combination of two cars connected 75 by a bridge, and adapted to be revolved bodily about a center, with inner and outer reflectors, a receiver, and secondary reflectors, substantially as specified.
7. The car E, mounted upon the circular 80 track F, in combination with the reflectors A B C, one of which is centrally located, substantially as shown and described.
8. The combination of the car E, reflectors A B C D, bridge I, receiver J, and car H, 85 mounted upon the track G, substantially as shown and described.
9. The combination of the car H, carrying a reflector, D, with the bridge I, receiver J, and car E, carrying reflectors, substantially as 90 shown and described.

In testimony whereof I affix my signature in presence of two witnesses.

WILLIAM CALVER.
